UNITED STATES PATENT OFFICE.

ALBERT KRAUTH, OF HAMILTON, OHIO; FRITZ G. DIESBACH ADMINISTRATOR OF SAID
ALBERT KRAUTH, DECEASED.

MANIFOLDING-MACHINE.

1,333,083.

Specification of Letters Patent.

Patented Mar. 9, 1920.

Application filed July 3, 1916. Serial No. 107,322.

To all whom it may concern:

Be it known that I, ALBERT KRAUTH, a citizen of the United States, and residing at Hamilton, in the county of Butler and 5 State of Ohio, have invented a new and useful Improvement in Manifolding-Machines, of which the following specification is a full disclosure.

My invention relates to manifolding machines or autographic registers, and in particular to devices for coöperating with the web or webs of paper supported and drawn over the writing table. The devices are arranged to engage through registering apertures in the paper to intercept the paper upon the table and provide for a paper engagement for its withdrawal from the machine.

An object of the invention is to provide 20 detents mounted to yield or move transversely to the plane of a writing table, and reciprocable in a direction longitudinal to the table and arranged in a spaced relation crosswise of the writing table. The detents 25 in their transverse motion are adapted to intercept the paper drawn over the writing table, by engaging through registering apertures in the paper, and are retracted for releasing the paper, and in their reciprocative motion in one stroke when engaged 30 with the paper, draw the paper therewith over the writing table a determined distance, sufficient for extracting the end of the paper from the machine for accessible manual 35 grasping; whereupon the detents are retracted and tripped for a return or retreat to a normal location for yieldingly bearing against the under surface of the paper upon the table for a successive paper intercepting 40 operation.

A further object of the invention is to provide lever actuated devices for operating and controlling said detents.

Various other features and objects of the 45 invention are readily discernible from the description of the accompanying drawings, which, in part, also relate to details of construction; the drawings illustrating a preferred embodiment of the invention, with 50 like characters of reference used to denote corresponding parts throughout the several views, of which:—

Figure 1 is a central vertical section through the machine containing my improvements.

Fig. 2 is a plan view taken from the under surface of the writing table, and of a portion thereof, represented as the forward portion, with the side frame shown in section. 60

Fig. 3 is an enlarged section on line 3—3, Fig. 2, viewed from a direction as shown by arrow on said latter figure.

Fig. 4 is an enlarged section taken on line 4—4, Fig. 2. 65

Fig. 5 is a plan view of a portion of web paper illustrating the same as apertured, with the apertures in spaced relation crosswise and lengthwise of the web and alined relatively. 70

Fig. 6 is a detail enlarged section on line 6—6, Fig. 2.

Fig. 7 is an enlarged section on line 7—7, Fig. 2, illustrating the parts in a normal position, and the detents assuming a position 75 as when engaged through the apertures in the paper over the writing table.

Fig. 8 is a view similar to Fig. 7, showing one of a sequence of operative steps or positions of the detents. 80

Fig. 9 is a similar view showing a second step in the operation of the detents.

Fig. 10 is an end elevation of the machine shown in Fig. 1.

Fig. 11 is a side elevation of the forward 85 portion of the machine.

The size of the machine as herein represented is one capable of being loaded with three supply webs of paper; the number of webs to a machine is optional. The webs 90 either in the singular or plural usually each comprise preprinted blank forms, as bills of lading, sales or record strips, required for a particular service. The webs are arranged to adapt them to be fed over the 95 writing table of the machine, and in a superposed relation when in the plural number for manifolding. The webs or strips of paper used are each apertured or perforated, the apertures arranged in series alined crosswise and lengthwise of the strip, as shown in Fig. 5, and the apertures are located in the blank space of the paper which divides the form data. The lengthwise spacing of apertures, therefore, may be said 100 to coördinate to measured or determined sheet or form lengths, as represented when torn from the continuous strip. The apertures, therefore, serve as indexes for determining the length of paper withdrawal, 105

110

and as a gage for alining and registering the several strips or webs in the superposed relation upon the writing table. As the paper is apertured at the time of printing, the 5 apertures are very accurately located with respect to the printing, and when the paper upon the writing table of the machine is engaged by intercepting devices as detents, entering or projecting through registering 10 apertures in the paper, controlling a paper withdrawing length accurately as to sheet size measurement, and also, to gage a sheet length properly with respect to a tearing-blade for severing the withdrawn portion 15 from the continuous strip. Thus the withdrawn severed sheets, in measurement, correspond accurately when compiled and bound.

Referring to the drawings, 1—1, represent 20 a pair of side frames, which may be of sectional form, as illustrated, forming a casing fixed to a base 2, with one section of each of the side frames hingedly mounted upon a second, with the opposite forward companion sections of both frames connected as a unit, and adapted to be swung forwardly for gaining access into the interior of the casing.

The side frames are provided with opposite supports arranged in pairs for journaling the webs of paper, each pair of supports engaging into the core of a web and yielding toward each other, applying a proper retarding tension upon the sides of the web roll necessary for a proper unwinding of 35 the paper. A writing table 3 is secured upon and supported between the side frames, and with its table surface slightly below the top edge of the side frames, whereby the side frames serve to guide the paper supported 40 upon and withdrawn over the writing table. The writing table and side frames, therefore, provide a channel for the paper for properly guiding the paper in its withdrawal from the machine, which channel is 45 of a width approximately equal to that of the paper with which the machine is to be loaded. A margin frame 4 bridges over the writing-table and is hingedly mounted to one of the side frames, or upon a carbon-holding receptacle 5 projectingly secured to 50 one of the side frames.

The foregoing described parts are common in machines of this class and may be referred to as fundamental elements, varying 55 in design and construction to meet the various requirements for the various styles of machines for the different manifolding and autographic register service.

The forward end of the margin frame is 60 bent acutely upward to form a flange 6 which serves to reinforce such margin-frame end, and provides an inclined support for the tearing-blade 7 secured to said flange. The cutting edge of the blade is at an elevation 65 slightly above the writing-table to

clear the paper and not interfere with the paper withdrawal. The margin-frame being hinged to one of the side frames, adapts it to be swung upwardly for accessibility to the paper upon the table and when closed 70 is suitably locked, and at its forward end by a spring latch member 8, fixed to a side frame 1, apertured to engage with a pin 9, projecting from an angle flange of the margin frame, see Fig. 11. 75

At the forward end of the writing-table paper intercepting devices are provided, which, as detents, yield transversely to the table to engage through apertures in the paper when brought into registry therewith for arresting the withdrawal of the paper; alining several superposed webs upon the writing table with respect to each other; automatically determining the length of withdrawal and confining the paper upon 80 the writing table against displacement. In producing the above results, the detents as paper interceptors operate and are analogous to the detents shown and described in the re-issue application, Serial No. 94,834, filed by 85 me May 1, 1916.

In the present invention the detents are further utilized when engaged with the paper for withdrawing the paper from the machine to bring an end of the paper beyond the tearing-blade, or extracted sufficiently for manually grasping the strip for a manual withdrawal, after which the detents are retracted and tripped to automatically retreat to their normal location and 90 bear against the under surface of the paper, so as to snap through successive apertures as the paper is drawn over the writing-table.

The construction disclosed provides for a pair of detents 10—10, each fixed respectively to a plate 11 and the plate 11 of each connected as a unit by a cross-strip 12, see Fig. 2. Each detent carrying plate is slidably mounted upon a flexible plate 13, and as both are of duplicate construction, only 100 one will be described in detail.

The plate 13 has a free forward end, and at its rear end is secured to the lower surface of the writing-table 3, by rivets or screws 14, so that the forward end of the 115 plate 13 yields away from the writing-table for transversely moving the detent 10. The detent has a stud portion 15, projected from the plate 11, to which the detent is secured, and engaged through a longitudinal 120 slot 16 in the plate 13, and connected to move transversely with the forward end of the plate 13, by a pin 17 engaged through the stud 15 of the detent. The rear end of the detent carrying plate 11 is angled and 125 notched to provide a notched flange 18, (see Fig. 6), which engages through a longitudinal notch 19 in the plate 13 for slidably mounting the plate 11 upon the plate 13.

The pins 20 connecting the cross-bar 12 130

with the plate 11 engage respectively through a longitudinal slot 21 in the plate 13 so that the detents of a series and their carriers as a unit are adapted to slidingly move or reciprocate upon their supporting plates 13 in a direction longitudinal to table 3, or in a paper withdrawing direction to draw the paper therewith when the detents are engaged with the paper. The detents 10 and their supports move transversely to the table, with the forward ends of the plates 13, which plates are connected by a cross-bar 22 to control the same as a unit. In retracting the detents from the paper apertures, they are moved below the table plane to a position free from the paper, enabling them to retreat to their normal location with their ends below the paper to bear against the under surface of the strip of paper immediately above the table. Such operation renders the detents free to snap into successive apertures when brought into registry therewith. The plates 11, connected as a unit, will be referred to as detent carriers, 25 for it is obvious, that the parts comprising the carrier could be made integral and adapted for supporting any number of detents as may be comprised in a series, but a pair being ample for the purpose intended, 30 relatively spaced, the spacing corresponding to a pair of aligned apertures crosswise of the paper, which is of a standard size in measurement to fit loose sheet binders.

The carrier is moved forward and controlled by the following instrumentalities:—

A flexible tongue 23 is secured to the cross-strip 12, see Fig. 2, with its free end engaging and sliding upon a block 24, in the reciprocating motions of the carrier, and in a forward motion moves beyond the end of the block, to permit it to yield to an abutting relation against the forward end of the block 24. Such abutting engagement between the tongue 23 and block 24 locks the carrier 45 against retreat until the detents have been retracted from their paper engagement. A flexible tongue 25 is mounted upon a reciprocating slide-bar 26, said slide-bar 26 being guidingly supported by straps secured upon the under face of the writing table 3. The end of the tongue 25 is projected to engage with the shouldered end 27 of the tongue 23, and also yields toward the block 24 upon which it slides. The tongues 23 and 25, 50 therefore, have their ends abuttingly aligned and engaged during the forward stroke of the slide-bar 26, until the end of the tongue 23 has been moved off of the block 24 destroying the tongue abutting alinement, so that they assume an offset relation, permitting the tongue 25 to pass over the tongue 23 with a continued forward motion of the slide-bar 26. Breaking such transmitting relation between the tongue enables the detents to be released and quickly retreated to

their normal location independent of a positive transmission control of the slide-bar 26. The slide-bar 26 continues in its forward stroke after disengagement from the detent carrier, for retracting the detent, and 70 freeing the carrier for its return to normal position.

To retract the detents, I provide the slide-bar 26 with an inclined cam block 28 arranged to engage the cross strip 22 connecting the plates 13 for flexing the plate 13 downward or in a direction away from the writing table. Such flexing or transverse motion of the plates 13, retracting the detents from the paper apertures, bringing the 80 ends of the detents below the table surface for a free retreating motion, it being understood that the cam 28 becomes effective after the detents have functioned for a determined paper withdrawing operation necessary to 85 extract the end of the paper a sufficient distance beyond the tearing-blade, so that the paper can be grasped by the operator for the manual withdrawal. The slide-bar 26 has a second cam or wedge element 29 projected 90 therefrom arranged to engage the end of the tongue 23 of the carrier to flex the tongue 23 and tongue 25 and bring the shouldered end of the tongue 23 to an elevation with the block 24, releasing the carrier for its return 95 to normal position. The tongue 23, in the return stroke of the carrier, slides between the block 24 and tongue 25. The retreating motion of the carrier is imparted by a pair of springs 30—30 connected respectively to 100 the detent studs 15 and under surface of the writing-table 3, as shown in said Fig. 2.

From the foregoing it will be observed that the detents in each alternate reciprocating stroke slide with the carrier upon the 105 support in different elevations, in the forward stroke at an elevation for engaging with the paper and in a return stroke at non-paper engaging plane or elevation.

The slide-bar 26 is reciprocated by lever 110 devices, comprising a lever arm 31, (see Fig. 1), having one end loosely connected to a bracket extension 32 projecting from the forward end of the slide-bar 26 and the opposite end of said arm 31 is fixed 115 upon a rock shaft 33 suitably journaled and supported within the side frames 1—1, as shown in Fig. 10. One end of the rock shaft projects beyond one of the side frames for receiving a hand-lever 34 which is fixed 120 to said shaft exterior of the casing.

A spring 35 is coiled around the rock shaft 33 with one end fixed to the shaft and its opposite end to the casing and is utilized for automatically returning said lever and 125 its connected parts to a normal position.

From the foregoing it will be observed that the detents yield transversely with the plate 13 for moving the detents into and out of a paper aperture engagement and in a di- 130

rection lateral to the writing table, and upon the plates 13 longitudinally to the writing-table and independently of their transverse motion, enabling the detents to be reciprocated longitudinally to the table at different elevations; at one elevation engaged with the paper for drawing the paper therewith in a forward direction, and at a second elevation released from the paper for a return stroke.

10 Now, assuming that the detents occupy the position as shown in Fig. 7, and, further assuming, that they are engaged through apertures in the paper upon the writing-table, which it is desired to feed forward so as to bring the end of the paper slightly beyond the tearing-blade sufficiently to be manually grasped for a continued manual withdrawal of the paper. Rocking the hand-lever 34 in a forward direction, will 15 correspondingly swing the lever arm 31, moving the slide-bar 26, and abuttingly engage the tongue 25 with the shouldered end 27 of the carrier tongue 23, so that the tongues as a unit move forward upon the block 24. The tongues bearing yieldingly against the face of the block 24 maintains them in abutting engagement as long as they continue to move in alinement over the face of the block 24 and correspondingly moves 20 the detent carrier and its detents, until the shouldered end of the tongue 23 is released from its engagement with tongue 25, or derailed from said block surface. As the tongue 23 passes off of the block it snaps to 25 an offset relation with the end of tongue 25. The tongue 25 continues in motion to the end of its stroke overlappingly upon the tongue 23, as shown in Fig. 8. As the slide block reaches its limit of forward motion, 30 the cam or wedge member 28 engages the cross-bar 22 flexing the plates 13, as shown in Fig. 9, moving the detents transversely and to a second elevation below the table surface, retracting the detents from and releasing the paper. After the detents have 35 been retracted sufficiently, the wedge or cam member 29 engages the shouldered end of the tongue 23, releasing the end of the tongue from its engagement with the end of block 24, moving the tongue 23 to an elevation enabling it to slide upon the block in a retreat or return direction between said block and tongue 25, as shown in Fig. 9, for 40 quickly restoring the detents to their normal location free from any lever control. Retracting the slide-bar 26, releases the plates 13 from the wedge or cam influence, leaving the detents free to snap and engage through a successive set of perforations as 45 the paper is withdrawn. The detents, as shown, are mounted to operate at the forward end of the table, each respectively engaging through a longitudinal slot in the writing-table and through a longitudinal slot in the margin-frame, as shown in Fig. 50

3. The margin-frame at such point confines the paper upon the table to prevent the paper from being raised under the influence of the detents when the detents engage or bear against the under surface of the paper, 70 as the paper is being withdrawn, insuring entry of the detents into the paper apertures when in registry.

The machine is provided with the usual brake devices for preventing reverse motion 75 of the paper, comprising a spring-tensioned blade 36, see Figs. 7, 8, 9 and 10, hinged upon a cross-rod or shaft 37, said blade projecting through a notch in the writing-table and adapted to bear against the cross-bar 80 portion of the margin-frame.

Having described my invention, I claim:

1. A device of the class described comprising a casing having a web supporting writing-table, a flexible detent supporting member mounted upon the under surface of the writing-table, a detent slidably mounted upon said support and adapted to engage through a registering aperture in the web of paper upon the table, the web of paper 90 longitudinally having apertures in spaced relation, and means for sliding said detent longitudinally of the table for drawing the paper over the table and yielding said support for extracting the detent from its paper engagement.

2. A device of the class described comprising a casing having a web supporting writing-table, flexible detent supporting means mounted upon the table, a detent 100 movable upon said support longitudinally of the table, and laterally with said support, adapting the detent to engage through a registering aperture in the paper upon the table, and when engaged with the paper 105 draw the paper over the table, means for moving said detent upon its support and for flexing said support at the end of a detent stroke.

3. A paper feeding and arresting device, 110 comprising a table for supporting a web of paper, the paper having apertures in spaced relation longitudinally, a detent carrier having a detent adapted to engage through a registering aperture in the paper, a guide 115 member for slidably supporting said detent carrier mounted to move said carrier to different elevations with respect to the plane of the table, to support and guide the carrier in detent paper engaging and non-engaging 120 planes relatively in alternate movements of reciprocation, and means for actuating said guide member.

4. A paper feeding and arresting device of the class described, comprising a table for 125 guidingly supporting a web of paper, the paper having apertures in a spaced relation longitudinally, a detent carrier having a detent projected angularly to the plane of the table, the detent adapted to engage 130

- through a registering aperture in the paper, a transversely yielding support upon which said carrier is mounted to slide in motions of reciprocation longitudinally of the table, 5 and at a different elevation in alternate carrier strokes, reciprocating actuating means adapted to engage said carrier to move the carrier therewith in one stroke direction, and to automatically release therefrom after 10 a determined translating distance and sequentially engage and transversely flex said support to change the carrier retreat stroke elevation and retract the detent from the paper engagement, and trip the carrier for 15 an automatic retreating stroke, and tension means for automatically moving said carrier in one of its reciprocating strokes.
5. In an autographic register comprising a suitable frame work from which strips of 20 paper are withdrawn, the combination with
- a stationary platen over which said paper passes longitudinally from the rear, of a reciprocated pin carrier slidably mounted beneath said platen, having vertically disposed pins located adjacent the forward end 25 of said platen that engages said paper, a depressible support for said carrier and pins, for moving said pins downward below the plane of said platen, means for moving said carrier forward, and means for depressing 30 said support at the forward limit of carrier movement.

In witness whereof I hereunto subscribe my name, as attested by the two subscribing witnesses.

ALBERT KRAUTH.
